CLAIM

We claim the ornamental design for a serving utensil, as shown and described.

DESCRIPTION

FIG. 1 is a perspective view of the serving utensil;

FIG. 2 is a side view of the serving utensil;

FIG. 3 is a top view of the serving utensil; and,

FIG. 4 is a bottom view of the serving utensil.

As shown in the drawings, the broken lines are for illustrative purposes only and form no part of the claimed design.
